CONTAINER

Arthur Rous, New York, N. Y., assignor to Federal
Carton Corporation, New York, N. Y., a corpora-
tion of New York

Application June 20, 1942, Serial No. 447,857

4 Claims.

(Cl. 229—17)

My invention relates to a new and improved container which has a pouring opening and a movable hand-operated gate for opening and closing the opening.

The principal objects of the invention are to produce a container of simple and efficient construction, which can be manufactured and assembled at low cost and which will be reliable in operation.

A particular object of my invention is to provide a carton which can be made by cutting and hinging a single blank, so that said blank can be folded into carton form and portions of said blank can be connected by means of adhesive or other suitable means, in order to form the completely assembled carton.

Other objects of the invention will be stated in the annexed description and drawings which illustrate a preferred embodiment thereof.

Fig. 1 is a perspective view which shows the gate in the operative position in which it closes the opening.

Fig. 2 is a perspective view showing the gate in its inoperative or open position and showing the carton tilted so as to discharge its contents through the opening. The contents may be any powder or other flowable material.

Fig. 3 is a partial front view of the improved container, showing part of the front wall broken away and showing the finger-hold of the gate in its operative position.

Fig. 4 is a section on the line 4—4 of Fig. 1.

Fig. 5 is a view similar to Fig. 4, showing the gate in its open position.

Fig. 6 is a plan view of the blank which is assembled by bending said blank along suitable hinge lines, and by pasting or otherwise connecting portions of said blank to each other, in order to form the complete assembled device.

While the carton may be made of any shape, and while the invention is not limited to the specific shape of carton which is illustrated herein, the particular embodiment illustrated has four upstanding walls, each of which is of greater height than width. The end walls of the carton are square in this particular embodiment. For convenience, the wall of the carton in which the opening is located is designated as the front wall.

Referring to Fig. 6, the carton blank is provided with side wall-members 1 and 2, a bottom-end wall-member 3, and a top-end wall-member 4. The front wall-member 5, in which the pouring opening 6 is located, is integral with one longitudinal edge of the side wall-member 1.

The rear wall-member 7 is integral with the other longitudinal edge of the side wall-member 1. The front and rear wall-members 5 and 7 are hingedly connected to the respective longitudinal edges of the side wall-member 1, along suitable hinge lines 8. The top end wall-member 4 and the bottom end wall-member 3 are connected at the respective lateral edges of the side wall-member 1, along similar hinge lines 8. The side wall-member 2 is hingedly connected to the respective lateral edge of the bottom end wall-member 3, along another hinge line 8. Whenever said reference numeral 8 is used in Fig. 6, it designates a hinge line. The reference numerals 8a indicate lines at which the blank is cut through-and-through.

The top end wall-member 4 is provided with lateral flaps 9 and 10. An opening 11, which is of greater diameter than the opening 6, is located in the flap 10. In this embodiment, the openings 6 and 11 are shown as being of circular shape, but said shape may be varied. The top end wall-member 4 is provided with a supplemental longitudinal flap 12, which has lateral flaps 14 and 15. The bottom end wall-member 3 is provided with supplemental lateral flaps 16 and 17. The side wall-member 2 is provided at one longitudinal edge thereof, with a lateral flap 18. The other longitudinal edge of said side wall-member 2 has a flap 23. This flap 18 and the side wall-member 2 are cut along lines 20a, in order to provide a gate 19, which has a base portion 20. Said base portion 20 is hingedly connected to the side wall-member 2 along the respective longitudinal hinge line 8. At the junction between the gate 19 and its base 20, the base 20 is cut along the arc 21a, to provide a finger hold 21. Hence, there is an imperforate portion 18a, between the end of gate 19 and the free longitudinal edge of said flap 18.

One of the advantages of the improved blank is that adhesive can be applied thereto and said blank can be assembled, by conventional machinery. However, the assembly of the blank by hand will be described, in order to explain the invention more fully.

In describing the assembly of the blank, it is assumed, for convenience, that the bottom end wall-member 3 is held in a horizontal plane. The respective side walls 1 and 2 are then bent upwardly along the respective lateral hinge lines 8, until said side walls 1 and 2 are in parallel vertical planes. The top end wall-member 4 is then bent downwardly along the respective lateral hinge line 8 until said member 4 is in a horizontal plane. The flap 12 is bent downwardly

along the respective hinge line 8 until said flap 12 is in a vertical plane and it abuts the inner surface of the top portion of the side wall-member 2.

The flap 10 is bent downwardly along the respective hinge-line 8 and the flap 16 is then bent upwardly along the respective hinge-line 8, so that flap 16 overlaps flap 10. The flaps 9 and 17 are similarly bent into similar overlapping relation. The overlapping portions of flaps 10 and 16 are connected by adhesive or other connecting means, and the overlapping portions of flaps 9 and 17 are similarly connected. Flap 14 is now turned to abut flap 10. Any suitable portions of flaps 10 and 14, such as their top portions, are connected by adhesive or by other means. The flap 14 can be dimensioned so as to overlap flap 16, or so that the bottom edge of flap 14 can abut or be a little above the top edge of flap 16. Flap 15 is similarly turned and connected to flap 9.

If desired, flap 10 can partially overlie and overlap flap 18. Flap 9 can overlap flap 17, or flap 17 can overlie flap 9.

The adjacent and abutting portions of the flaps 14 and 18 are connected by adhesive or other means, so that flap 14 closes a part of the opening in flap 18 which is formed by the through-and-through cut-lines 20a. The adjacent faces of flaps 15 and 23 are also connected by adhesive. I can omit the connection between flaps 14 and 10, and between flaps 15 and 9. Flap 18 is turned and connected by adhesive or the like to flaps 10 and 16, and flap 23 is similarly turned and connected to flaps 9 and 17. Front wall 5 is now turned and connected to flap 18, leaving the gate 19 free, and rear wall 1 is turned and connected to flap 23, thus completing the carton. The flaps 14 and 23 may be unconnected by adhesive to flaps 9 and 17.

The gate 19 is thus freely slideable in a frame of the flap 18, and flap 14 is located between gate 19 and flap 10. The front wall 5 overlies the gate 19, and the small hole 6 is aligned with the large hole 11, so that said holes have a common axis. Both holes 6 and 11 are aligned with the frame which is formed in flap 18, by the cut-lines 20a.

The tab 21 is integral with base 20. The line 21a may be a through-and-through cut-line or it may be a line along which the blank is only weakened without being cut through-and-through, as by scoring, so that the tab 21 may be pried out of base 20, and said tab 21 is then turnable until it is perpendicular to base 20. The cut-out 5a in front wall 5 facilitates the manipulation of gate 19. The gate 19 can be releasably sealed at the factory, after the carton has been filled and closed. This can be done by an extension tab of front wall 5, which can be detachably connected to wall 5 along the arcuate line of cut-out 5a. In such case, the line 5a is a line of scoring. Said sealing extension tab can be releasably connected by adhesive to side wall 2, without connecting the same to gate 19 or base 20.

The reference numeral 18a indicates a longitudinal strip of the flap 18 which is free from the frame which is defined by the cut-lines 20a.

While I have shown the blank as perforated at the holes 6 and at 11, it is to be understood that in actual practice the front wall 5 and the flap 10 are imperforate and they are provided with score lines at the edges of the openings 6 and 11, so that said score lines define closure disks which close said openings 6 and 11, when the carton is filled and closed at the plant. These

closure disks can be forced inwardly into the carton by slight pressure, thus opening the front wall 5 and the flap 10 at the openings 6 and 11.

The hinge line 8, by means of which said gate-base 20 is hingedly connected to the member 2, is indicated by the reference letter H in Figs. 1, 2 and 5.

When the carton is shipped, the finger-hold tab 21 is coincident with the side wall 2. In order to use the gate, the finger-hold 21 is turned from the inoperative position which is shown in Fig. 1, to the operative position which is shown in Fig. 2. The gate 19 is readily slideable from the closing position which is shown in Fig. 1 and in Fig. 4, to the opening position which is shown in Fig. 2 and in Fig. 5, and back to the closing position which is shown in Fig. 1 and in Fig. 4.

It will be noted that the carton has successive faces, each pair of successive faces being in angular relation. In this particular embodiment, successive faces are perpendicular to each other. A selected face of the carton has a plurality of walls. In the particular embodiment, said selected face of the carton has the walls 10, 18 and 5. The innermost wall 10 and the outermost wall 5 are provided with aligned openings. A gate is cut out of the material of the intermediate wall 18. Said gate has an integral base which is turnably connected to a wall of the carton at the face 30 of the carton which immediately succeeds said selected face.

While I prefer to provide three walls at the selected pouring face of the carton, the invention is not limited to this feature.

35 I have shown a preferred embodiment of my invention, but it is clear that numerous changes and omissions can be made without departing from its spirit.

I claim:

40 1. A carton which has a pouring face, said pouring face having an inner wall and an outer wall and an intermediate wall which is located between said inner wall and said outer wall, said inner wall and said outer wall having aligned 45 pouring openings, said intermediate wall having a cut-out, said cut-out being aligned with said pouring openings, said intermediate wall having a movable relative thereto, said gate being movable to an operative position in which a part 50 of said gate is located between said pouring openings, said gate being also movable to an inoperative position in which it is spaced from said openings, said gate being integral with a gate-base, said gate-base being turnably connected to a wall 55 of said carton which is inclined to and which is integral with said intermediate wall.

2. A carton which comprises an integral blank which is folded into carton shape, said blank comprising a front wall member which constitutes a front wall of the assembled carton, said front wall member having a pouring opening, said carton also comprising a flap and a side-wall member, said flap being located adjacent to and inwardly of said front wall of the assembled carton, the side-wall member being immediately adjacent to and being angularly disposed to said flap in the assembled carton, said flap and said side-wall member being cut through and through along two opposed cut lines and along an additional intermediate cut line, said cut lines being spaced wholly from the edges of said flap and of said side-wall member, said intermediate cut line being located only in said flap, the material of said flap which is located between said opposed 70 cut lines and said intermediate cut line comprising

ing a gate which is movable to a closing position at which it obstructs said opening, the material of said side-wall member which is located between said opposed cut lines comprising a base for said gate, said base being bendable relative to the side-wall member, said base being coincident with the side-wall member when the gate is in the closed position.

3. A device according to claim 2, in which said gate and said base are bent relative to each other at an edge line of said carton, said base being cut to provide a finger tab which is bendable relative

to said gate and relative to said base along said respective edge line, when the gate is in the closed position.

4. A device according to claim 2, in which said carton has a second flap which is provided with an additional perforation, the perforations of said perforated flaps being aligned in the assembled carton, said first-mentioned flap being located between said front wall member and said second flap in the assembled carton.
